[57] CLAIM

The ornamental design for a framing component, as shown and described.

DESCRIPTION

FIG. 1 is a perspective view of the framing component.

FIG. 2 is a plan view of the upper surface of the framing component shown in FIG. 1 being identical to the opposed bottom surface (not shown).

FIG. 3 is the left-hand side view of FIG. 2.

FIG. 4 is the rear view of the framing component as seen from behind of FIG. 1.

FIG. 5 is a bottom view of FIG. 2.

FIG. 1

FIG. 3

FIG. 2

FIG. 4

FIG. 5
